UNITED STATES PATENT OFFICE.

FRANK A. REARDON, OF CANTON, OHIO.

DESIGN FOR A HOLDER FOR ICE-CREAM BOXES AND THE LIKE.

Application filed June 14, 1928 Serial No. 27,133. Term of patent 7 years.

To all whom it may concern:

Be it known that I, FRANK A. REARDON, a citizen of the United States, residing at Canton, in the county of Stark and State of Ohio, have invented a new, original, and ornamental Design for Holder for Ice-Cream Boxes and the Like, of which the following is a specification, reference being had to the accompanying drawing, forming part hereof.

The figure is a perspective view of a holder for ice-cream boxes and the like, showing my new design.

I claim:

The ornamental design for a holder for ice-cream boxes and the like, as shown.

In testimony whereof I affix my signature.

FRANK A. REARDON.
